FIG. 4 is a rear elevational view thereof;

FIG. 5 is a top plan view thereof;

FIG. 6 is a bottom plan view thereof;

FIG. 7 is a perspective view of a second embodiment of the mounting box for a trailer hitch electrical connector, the utilitarian mounting slot shown in phantom is for illustrative purposes only and forms no part of the claimed design;

FIG. 8 is a front elevational view thereof;

FIG. 9 is a rear elevational view thereof;

FIG. 10 is a top plan view thereof; and,

FIG. 11 is a bottom plan view thereof.

The sole difference in the second embodiment is the arcuate opening at the bottom of the front and rear member.
